INVENTOR
Joseph E. Keniston.

ATTORNEY

UNITED STATES PATENT OFFICE.

JOSEPH E. KENISTON, OF ALBANY, CALIFORNIA.

DIE-HEAD HOLDER.

1,264,088.

Specification of Letters Patent. Patented Apr. 23, 1918.

Application filed June 15, 1917. Serial No. 174,985.

To all whom it may concern:

Be it known that I, JOSEPH E. KENISTON, a citizen of the United States, residing at Albany, in the county of Alameda and State 5 of California, have invented certain new and useful Improvements in Die-Head Holders, of which the following is a specification.

This invention relates to die head holders, 10 and is adapted particularly for use in connection with power or hand pipe threading and cutting machines.

The primary object of the invention is to provide an improved holder adapted for use 15 with machines of the type above referred to, and wherein the die heads of various sizes for use with the machine are supported in close proximity to the carriage of the machine, and which may be quickly and 20 easily applied to or removed from the carriage.

A further object of the invention is to provide a holder for die heads which is capable of holding or accommodating a 25 number of die heads of various sizes, and wherein the holder is located in a position convenient to the machine, and at the same time is so located as to not interfere with the operations of the machine or the efforts 30 of the machine operator.

Still further objects reside in providing a holder of the character described which shall be of extremely simple and inexpensive construction, which is capable of being 35 readily applied to the machine and which requires no attention after once being installed, and which will facilitate the work of the operator of the machine with which the improved holder is used.

With these objects in view together with others which will appear as the description proceeds, the invention resides in the novel formation, combination and arrangement of parts all as will be described more fully 45 hereinafter, illustrated in the drawings and particularly pointed out in the claims.

In the drawing:

Figure 1 is an end elevation of a holder constructed in accordance with the invention, the holder being illustrated removed from the machine, and

Fig. 2 is a sectional view taken through a part of a conventional form of threading or cutting machine, and illustrating the 55 proximate location of a holder constructed in accordance with the invention.

Referring now to the drawing, 5 indicates the frame of a conventional form of pipe threading and cutting machine, upon which a carriage 6 is slidably mounted. It 60 will be understood that this carriage is capable of moving longitudinally of the frame upon suitable track-ways, and the movements of this carriage may be controlled in any approved manner. The carriage 65 is adapted to support the die heads indicated generally at 7, and is equipped with guides 8 for this purpose. The heads are introduced to the guideways from the ends of the carriage, and require sliding 70 movement for their application or removal from the carriage.

The invention comprehends the arrangement of a frame 9 adjacent the machine, and which frame carries a plurality of 75 racks or holders indicated at 10, the said holders being adapted to contain die heads for use upon the machine. These holders or racks are equipped with guides 11 similar to those upon the carriage supporting the 80 die heads, and between which the die heads are adapted to fit. In the present instance, the frame 9 is provided with a pair of legs 12, the latter being bolted or in any other manner secured to the threading machine, and the 85 frame is positioned upon the machine in such manner that the racks carried thereby are disposed at their ends adjacent and slightly removed from the carriage 6 upon the machine. It will also be observed, particularly 90 in Fig. 2 of the drawing, that the guideways 11 upon the racks 10 are aligned with the guides 8 upon the carriage so that the die heads may be slid either from the carriage into the racks 10, or from the racks into 95 the guides upon the carriage. There may be any desired number of racks 10 upon the frame 9, and the racks are adapted to accommodate the die heads for cutting or operating upon work of different sizes.

When it is desired to apply a die head to the carriage, the latter is moved longitudinally of its supporting frame until the guideways 8 thereof are in register with the guideways 11 upon the rack which supports 105 the die head of the desired dimension. The die head is then moved by being slid longitudinally of the guideways 11 until the same moves into the trackways 8 upon the carriage. When it is desired to remove the 110 die heads from the carriage the reverse of this operation is performed.

It is obvious from this construction that I have provided an extremely simple and yet thoroughly efficient means for holding the die heads for use in connection with machines of the character mentioned, and by the use of such a rack, the labor and inconvenience incident to the lifting and carrying of the heavy dies is wholly obviated.

While the present disclosure is that of what is believed to be the preferred embodiment of the invention, it is to be understood that the invention is not limited thereto, but that various changes in the minor details of construction, proportion, and arrangement of parts may be resorted to if desired without departing from the spirit of the invention as defined by the appended claims.

What is claimed is:

1. The combination with a machine having a movable carriage provided with guides adapted to hold the die heads; of a frame secured to said machine, a plurality of racks supported by said frame, the ends 25 of said racks being disposed in close proximity to the path of travel of said carriage, and trackways upon said racks and in alignment with the guides upon said carriage.

2. The combination with a machine having a movable carriage provided with guides adapted to hold die heads; a frame secured to one side of said machine, a plurality of racks carried by said frame, one end of each of said racks being disposed in close proximity to the path of travel of said carriage, and trackways upon each rack with which the guides upon said carriage are adapted to align when the said carriage is moved a predetermined distance.

3. The combination with a machine having a movable carriage provided with guides adapted to hold die heads; of a frame secured to said machine at one side thereof and disposed parallel to the adjacent edge of said machine, a plurality of racks arranged in spaced parallel relation on said frame, trackways in said rack to receive the die heads on said machine, and the said trackways being disposed at right angles to said machine.

In testimony whereof I affix my signature in presence of two witnesses.

JOSEPH E. KENISTON.
